A. A. MILLER

FLUE STOPPER

Filed March 28, 1923

Inventor:
Arthur A. Miller
Watson E. Colman
Atty

UNITED STATES PATENT OFFICE.

ARTHUR A. MILLER, OF TEBBETTS, MISSOURI.

FLUE STOPPER.

Application filed March 28, 1923. Serial No. 628,311.

To all whom it may concern:

Be it known that I, ARTHUR A. MILLER, a citizen of the United States, residing at Tebbetts, in the county of Callaway and State of Missouri, have invented certain new and useful Improvements in Flue Stoppers, of which the following is a specification, reference being had to the accompanying drawings.

10 This invention relates to certain improvements in flue stoppers and it is an object of the invention to provide a device of this general character embodying novel and improved means whereby the stopper is effectively maintained in applied position.

15 It is also an object of the invention to provide a novel and improved device of this general character wherein the stopper is operatively engaged with relatively movable members adapted to engage the walls of a flue or the like whereby the stopper is effectively maintained in applied position.

20 The invention consists in the details of construction and in the combination and arrangement of the several parts of my improved flue stopper whereby certain important advantages are attained and the device rendered simpler, less expensive and otherwise more convenient and advantageous for 25 use, as will be hereinafter more fully set forth.

30 The novel features of my invention will hereinafter be definitely claimed.

35 In order that my invention may be the better understood, I will now proceed to describe the same with reference to the accompanying drawings, wherein:

40 Figure 1 is a view partly in section and partly in top plan illustrating a flue stopper constructed in accordance with an embodiment of my invention and in applied position.

45 Figure 2 is a sectional view taken substantially on the line 2—2 of Figure 1.

50 Figure 3 is a view in perspective of the hook carrying shank and the part associated therewith, the same being shown in separated relation.

55 As disclosed in the accompanying drawings, 1 denotes a stopper or cover of requisite dimensions and which is adapted to be disposed over the outer or open end of a flue opening. Extending axially through the stopper or cover 1 is a member 2 provided at its outer end with an enlargement or head 3 which has close contact with the

stopper or cover 1 when the device is in applied position. The opposite or inner end portion of the member 2 is tubular as at 4 and has in threaded engagement therewith 60 an elongated member or rod 5. The outer end portion of the rod 5 is provided with an inwardly facing hook 6 which is adapted to be engaged over an elongated nut 7.

Engaged with the opposite end portions 65 of the nut 7 are the reversely threaded rods 8 provided at their outer ends with the arcuate cross members or braces 9 which, when the device is in applied position, are adapted to have close contact with the inner walls of the flue opening F. The rods 8 outwardly of the feet or braces 9 are continued by the angularly related pointed members 10 which are adapted to penetrate the walls of the flue opening when the device is applied, said pointed members 10 are disposed toward the outer or open end of the flue opening so that it will be assured that the device will be effectively maintained 70 in applied position.

In applying my improved stopper, the nut 7 and the members directly associated therewith are first suitably positioned within the flue opening and the nut turned in a direction to force the rods 8 outwardly to 75 cause the feet or braces 9 to have close contact with the inner walls of the flue opening and at the same time to effect the requisite penetration of the pointed members 10. The hook 6 of the member or rod 5 is then engaged over the nut 7, said nut at its central portion being provided with a peripheral groove 11 to receive said hook. The stopper or cap 1 is then applied with the member 2 in proper threaded engagement with the 80 member or rod 5 and by proper rotation of the member 2, preferably through the instrumentality of the enlargement or head 3 the stopper or cover 1 is effectively maintained 85 in applied position.

From the foregoing description it is thought to be obvious that a flue stopper constructed in accordance with my invention is particularly well adapted for use by reason of the convenience and facility with which it may be assembled and operated, and it will also be obvious that my invention is susceptible of some change and modification without departing from the principles and spirit thereof and for this reason I do 100 not wish to be understood as limiting myself to the precise arrangement and formation of 105 110

the several parts herein shown in carrying out my invention in practice except as hereinafter claimed.

I claim:

- 6 1. A stopper for a flue opening comprising in combination, a cap, a nut, reversely threaded rods engaged with the opposite ends of the nut, the outer ends of the rods being provided with penetrating means, a 10 member engageable with the nut, and a member disposed through the cap and in threaded engagement with the first named member.
- 15 2. A stopper for a flue opening comprising in combination, a cap, a nut, reversely threaded rods engaged with the opposite ends of the nut, the outer ends of the rods being provided with angularly related 20 penetrating means, a member engageable with the nut, and a member disposed through the cap and in threaded engagement with the first named member, and feet carried by the 25 outer portions of the rods for close contact with the wall of the flue opening.

In testimony whereof I hereunto affix my signature.

ARTHUR A. MILLER.
